Patented Aug. 6, 1912.

UNITED STATES PATENT OFFICE.

HERMANN BUSCHER, OF LANGERFELD, GERMANY.

BRAIDING-MACHINE.

1,034,688.

Specification of Letters Patent.

Patented Aug. 6, 1912.

Application filed March 14, 1910. Serial No. 549,123.

To all whom it may concern:

Be it known that I, HERMANN BUSCHER, a citizen of the German Empire, residing at Langerfeld, in the Province of Westphalia and Kingdom of Prussia, Germany, have invented certain new and useful Improvements in Braiding-Machines; and I do hereby declare the following to be a full, clear, and exact description of the invention, such as will enable others skilled in the art to which it appertains to make and use the same.

This invention relates to braiding machines using devices for temporarily moving the bobbins out of the track of the drivers to temporarily render said bobbins inoperative and for subsequently restoring said bobbins to said track.

The object of the invention is to simplify the construction of such machines and improve their operation.

To this end the said invention consists of the construction and combination of parts hereinafter particularly set forth.

15 The drawing illustrates several embodiments of the invention, by way of example.

In said drawing: Figure 1 is a plan of the first embodiment, part of the upper track-plate being removed, and Fig. 2 is a cross-section on the line A—A of Fig. 1.

In the drawing, 1 is the upper track-plate of the new machine in which the track 2 for the bobbins 3 is provided. At the places where the bobbins cross, the points of the track-plate are removed alternately at the one and the other side of the track and the track is thereby flattened. Alternately at the inner side and outer side of the track there are arranged at the crossing places 10 switches 4 in a well-known manner and opposite said switches there are arranged at the other side of the track at the flattened parts of the same and below the track-plate withdrawers 5. The latter possess at their 15 ends, facing the bobbin track an upwardly directed projection 6 which extends from side to side and which projects to such an extent into the bobbin track that it intercepts the bobbins when they are elevated by the drivers 7 and leads them out of the reach of their drivers. Each of the withdrawers 5 is fastened on a rod 9 which is displaceable in a vertical direction and which is guided in the upper track-plate 1 20 and in the under plate 8, and each withdrawer is also guided while being vertically

displaced by means of a pin 10 projecting downward from the track-plate with which pin the slotted end of each withdrawer engages. Usually each rod 9 is held up at 60 such a height by means of a spring 11 engaging with it and secured to the under plate 8 that the projections 6 on the withdrawers 5 come within reach of the bobbin pins, so that the bobbins are led in the 65 manner described above out of the track and are consequently brought to a standstill.

If the rod 9 is pulled down by the jacquard cord 12 connected with it, then the projection 6 on the withdrawer 5 releases 70 the bobbin again and the latter can be pushed back again into the track. For this purpose there is in the case of the embodiment shown in Figs. 1 and 2 a pawl 13 pivotally connected with the rod 9 above the 75 track-plate 1, which pawl is pressed by a spring 14 against a pin 16 mounted in a support 15, so that the lower end of the pawl although resting just above the track-plate does not come into contact with the 80 latter, so that on the pawl being shifted the friction is reduced and the track-plate is not damaged thereby. On the descent of the rod 9 the pawl 13 moves out laterally and consequently strikes against the base of 85 the bobbin and pushes the bobbin back again into the track where it is clasped by the driver and driven on. The upstroke of the rod 9 is brought about under the action of the spring 11. Should the latter become 90 weak and then be no longer able to raise the rod 9 with the withdrawer, said rod and withdrawer are raised positively by the toothed driving wheels 17 of the bobbin-drivers. These toothed wheels possess on 95 their upper sides wedge-shaped elevations 18 which, on the wheel rotating, slide under downwardly projecting projections 19 on the withdrawers 5 and so raise the latter. It is not necessary for all of the toothed 100 wheels 17 to possess the elevations 18, on the contrary it is sufficient if one wheel out of two is provided with such elevations, as each wheel comes into contact with two neighboring withdrawers 5 which are, however, situated at different sides of the track.

What I claim as my invention and desire to secure by Letters Patent is:—

1. The combination in a braiding machine of a track, bobbins engaging therein, drivers 110 for driving said bobbins, a vertically displaceable rod projecting above the track-

- plate, a bobbin-withdrawer mounted on said rod, and a pivoted spring-influenced pawl on the upper end of said rod adapted on the descent of the latter to move out laterally 5 above the track-plate and push a bobbin back into the track within reach of a driver.
2. The combination in a braiding machine of a track, bobbins engaging therein, drivers for driving said bobbins, a vertically dis- 10 placeable rod projecting above the track-plate, a bobbin-withdrawer mounted on said rod, a pivoted spring-influenced pawl on the upper end of said rod adapted on the descent of the latter to move out laterally 15 above the track-plate and push a bobbin back into the track within reach of a driver, and a support for said pawl adapted to maintain the pawl just above the upper surface of the track-plate.
- 20 3. The combination in a braiding machine of a track, bobbins engaging therein, drivers for driving said bobbins, a vertically dis- placeable rod projecting above the track-plate, a bobbin-withdrawer mounted on said rod, a pivoted spring-influenced pawl on the upper end of said rod adapted on the descent of the latter to move out laterally 25 above the track-plate and push a bobbin

back into the track within reach of a driver, and a support situated on the track-plate 30 and provided with a pin adapted to maintain the pawl just above the upper surface of the track-plate.

4. The combination in a braiding machine of a track, bobbins engaging therein, drivers 35 for driving said bobbins, driving wheels for driving said drivers said wheels having on their upper surfaces wedge-shaped projec- tions, a vertically displaceable spring-in- fluenced rod, a bobbin-withdrawer mounted 40 on said rod, said withdrawer having a down- wardly projecting projection on its under surface adapted when the rod is in its lower- most position to engage said wedge-shaped projections on the driving-wheels, and a 45 member connected with said rod and adapted on the downward movement of the rod to press a bobbin back into the track within reach of a driver.

In testimony whereof, I have signed my 50 name to this specification in the presence of two subscribing witnesses.

HERMANN BUSCHER. [L. s.]
